[57] CLAIM

The ornamental design for a combined fuel pump dispensing handle lever holder and key ring, as shown and described.

DESCRIPTION

FIG. 1 is a top plan view of a combined fuel pump dispensing handle lever holder and key ring showing my new design;

FIG. 2 is a right side elevational view thereof, the left side elevational view being the mirror image thereof;

FIG. 3 is a front elevational view thereof;

FIG. 4 is a rear elevational view thereof;

FIG. 5 is a bottom plan view thereof; and

FIG. 6 is a right side elevational view of the holder inserted into a fuel pump dispensing handle.

The broken line disclosure in FIG. 6 showing a portion of a fuel pump dispensing handle is for illustrative purposes only and forms no part of the claimed design.
